DESK CLOCK OR THE LIKE

Richard Newman, Forest Hills, N. Y., assignor to Newman Exclusive Gift Mfrs., Inc., New York,
N. Y.

Application March 1, 1950, Serial No. 8,244

Term of patent 3½ years

(Cl. D42—7)

To all whom it may concern:

Be it known that I, Richard Newman, a citizen of the United States, residing at Forest Hills, New York, in the county of Queens and State of New York, have invented a new, original, and ornamental Design for a Desk Clock or the like, of which the following is a specification, reference being had to the accompanying drawing, forming part thereof.

Fig. 1 is a top plan view of a desk clock or the like, showing my new design;

Fig. 2 is a side elevational view; and

Fig. 3 is a bottom plan view of the same looking in the direction of the arrows 3—3 on Fig. 2.

Both side views of Fig. 1 are similar.

I claim:

The ornamental design for a desk clock or the like, as shown and described.

RICHARD NEWMAN.
